(57) **CLAIM**

The ornamental design for a fuel tank for ship as shown and described.

DESCRIPTION

The patent or application file contains at least one drawing executed in color. Copies of this patent or patent application publication with color drawing(s) will be provided by the Office upon request and payment of the necessary fee.

1. Fuel tank for ship

1.1 is a front elevation view of a fuel tank for ship embodying our new design;

1.2 is a rear elevation view thereof;

1.3 is a left side elevation view thereof;

1.4 is a right side elevation view thereof;

1.5 is a top plan view thereof;

1.6 is a bottom plan view thereof; and

1.7 is a perspective view thereof.

The broken lines depicting a boundary around the de-emphasized elements, and the de-emphasized elements within, illustrate portions of the fuel tank for ship which form no part of the claimed design.
